ANTISEPTIC TELEPHONE-MOUTHPIECE.

956,953.

Specification of Letters Patent.

Patented May 3, 1910.

Application filed October 7, 1909. Serial No. 521,514.

To all whom it may concern:

Be it known that we, WILLIAM M. ENGLISH and HARRY M. LICHTENSTEIN, citizens of the United States, residing at San Francisco, in the county of San Francisco and State of California, have invented new and useful Improvements in Antiseptic Telephone-Mouthpieces, of which the following is a specification.

10 The object of the present invention is to provide a simple, cheap, and effective antiseptic telephone mouthpiece.

In the accompanying drawing, Figure 1 is a broken side elevation of the mouth-piece, 15 a portion of the transmitter being shown in dotted lines; Fig. 2 is a longitudinal section thereof; Fig. 3 is a section on the line 3—3 of Fig. 2.

Referring to the drawing, 1 indicates a 20 portion of a telephone transmitter to which our improved device is shown as attached. Said device comprises a bell-shaped mouth-piece 2, formed of glass or other plastic material, and a union or shell 3 formed of thin 25 sheet metal. Said union is of a general cylindrical shape, but is formed at its rear end with threads 4, which are adapted to screw within the central socket of the telephone transmitter. Its outer or front end 30 is closed by a wall 12, perforated, as shown at 11, to permit the sound producing vibration to pass therethrough. In order to secure the shell or union within the mouth-piece, said shell is formed, in its cylindrical 35 wall, and at the end next to the transverse wall 12, and also in said wall 12, with slots 7, which extend longitudinally in said cylindrical wall and radially in said transverse wall. Three such slots 7 are here shown, but 40 there may be any suitable number. At the periphery of the transverse wall 12, and preferably centrally between each pair of slots 7, are formed knobs 6 which are adapted to enter sockets or recesses 8 formed in the 45 inner end 5 of the mouth-piece. The slots 7 are of such width that the sections of the transverse wall 12 and of the cylindrical wall formed thereby can be compressed sufficiently to permit the knobs 6 to pass within 50 the inner end 5 of the mouth-piece, until said knobs arrive at the sockets 8, whereupon they spring into said sockets, and securely connect the union to the mouth-piece. Said union is secured within said mouth 55 piece so that its front wall is behind but in

close proximity to a deep circumferential internal groove 10. In this groove can be removably inserted a string or loop 9 of absorbent material, such as wicking, which is saturated with formaldehyde or other suitable disinfectant, and can readily be removed from time to time and replaced by fresh material.

The saturated wicking or other absorbent material constantly gives off vapor, which 65 fills the interior of the mouth-piece, and destroys any germs which might enter in the ordinary use of the telephone.

The principal advantages of our invention are its cleanliness, cheapness, simplicity, and 70 effectiveness. Glass has absolutely no porosity, and therefore does not harbor germs, dust or the like, which can easily be removed therefrom. As to its cheapness and simplicity, it will be observed that the device 75 itself comprises only two parts, each of which costs but little to manufacture, and the two parts are easily assembled. The device is very effective, as the absorbent material contains sufficient disinfecting liquid 80 to permeate the mouth-piece with its vapor and thus thoroughly disinfect it.

We claim:

1. An antiseptic telephone mouth-piece comprising a flaring mouth-piece proper 85 made in a single piece, formed near the inner end with a deep circumferential internal groove adapted to receive absorbent material, and a union for connecting said mouth piece with the transmitter, secured within 90 the mouth piece, and consisting of a cylindrical metallic shell, formed at one end with a perforated wall arranged within said mouth piece wholly behind said groove, but in close proximity thereto, said shell ex- 95 tends wholly behind said wall and threaded on its rear end to screw within the central socket of the transmitter, substantially as described.

2. An antiseptic telephone mouth-piece 100 comprising a flaring mouth-piece proper, and a union for connecting said mouth-piece with the transmitter, consisting of a cylindrical metallic shell threaded to screw with in the central socket of the transmitter and 105 formed at the end remote from the transmitter with a perforated wall, the mouth-piece being formed immediately outside said wall with a deep circumferential internal groove adapted to receive absorbent 110

material, said shell being formed with slots in the wall and the part of the shell adjacent thereto, whereby said part can be compressed to enter said mouth-piece, substantially as described.

3. An antiseptic telephone mouth-piece comprising a flaring mouth-piece proper, and a union for connecting said mouth-piece with the transmitter, consisting of a cylindrical metallic shell threaded to screw within the central socket of the transmitter and formed at the end remote from the transmitter with a perforated wall, the mouth-piece being formed immediately outside said wall with a deep, circumferential internal groove adapted to receive absorbent

material, said shell being formed with slots in the wall and the part of the shell adjacent thereto, whereby said part can be compressed to enter said mouth-piece, and being 20 also formed with knobs, the mouth-piece being formed with sockets to receive said knobs, substantially as described.

In testimony whereof we have hereunto set our hands in the presence of two sub- 25 scribing witnesses.

WILLIAM M. ENGLISH.
HARRY M. LICHTENSTEIN.
